United States Patent Office.

EDMUND BENNETT, OF NANKIN, MICHIGAN.

Letters Patent No. 78,641, dated June 9, 1868.

IMPROVEMENT IN POTATO-DIGGERS.

The Schedule referred to in these Letters Patent and making part of the same.

TO WHOM IT MAY CONCERN:

Be it known that I, EDMUND BENNETT, of Nankin, in the county of Wayne, and State of Michigan, have invented a new and useful Improvement in Potato-Diggers; and I do declare that the following is a true and accurate description thereof, reference being had to the accompanying drawings, and to the letters of reference marked thereon, and making a part of this specification.

Figure 1 is a side view of my invention.

Figure 2 is an opposite side view of the same.

Figure 3 is a vertical sectional view of the same.

Figure 4 is a view of the slotted scoop.

The nature of my invention consists in so constructing an apparatus for digging potatoes, that it will effectually separate the vines from the potatoes, and thoroughly clean the potatoes, and deliver them, ready for loading, at the rear of the apparatus.

Similar letters indicate like parts in each figure.

In manufacturing my apparatus, I first make a suitable frame and box, A, hung upon proper axles, C, and wheels, B. Upon the inner side of the wheel B, in fig. 1, I attach a driving cog-wheel, D, (also shown in the sectional view, fig. 3,) which meshes upon one side into the pinion E, which pinion gives motion to the cog-wheel F upon the shaft. Upon the opposite side, this same cog-wheel D meshes into the pinion H, upon the shaft I. To the front of the frame and box A, I attach a slatted scoop, J, set at the proper angle to readily pass under the hill of potatoes to be dug. The entire hill, tops and potatoes, are taken up by this slatted scoop, and, as the apparatus is drawn forward, are forced up until they reach the curved teeth upon the endless chain K, which is carried by the shaft G, when the curved teeth tear off the vines, while the potatoes drop under other curved teeth in the endless belt L, which is carried by the shaft I. These curved teeth in the endless belt L force the potatoes back upon the shaker M, which should be constructed of wire, and through the openings of which the dirt is allowed to fall, while the potatoes are delivered at the rear of the machine. N is a shield to raise the teeth of the endless chain K, so that they will not interfere with the teeth in the endless belt L. O is another cog-wheel, placed upon the opposite end of the shaft G, and meshes into the pinion P, and operates the lever Q, and gives motion to the shaker M. R is a lever, to which is attached the cord or chain S, which passes over the fulcrum T, by means of which the driver can raise or lower the front of the apparatus as he may desire. U is an adjustable seat, working upon the rods V. W is an adjustable attachment, to which to fasten the shafts or tongue for the horses. X are small wheels, which are designed to run in the dead furrows, to sustain the front of the apparatus.

What I claim as my invention, and desire to secure by Letters Patent, is—

1. The method of separating the vines from the potatoes, by the curved teeth in the endless chain K, and endless belt L, and shield N, arranged substantially as described and for the purpose specified.

2. The combination of the above with the frame or box A, the wheels B, the axles C, the cog-wheels D and O, the pinions E, H, and P, the shafts G and I, the shaker M, the wheels X, the slatted scoop J, the lever R, the cord or chain S, and the fulcrum T, when constructed substantially as and for the purpose described.
